CONVEYER FOR BRANDING MACHINES

Jarl Pearson, Berkeley, Calif.

Application April 16, 1941, Serial No. 388,856

8 Claims. (Cl. 198—33)

The invention relates to a continuously operable machine for imprinting trade-marks and/or other matter on globate articles which do not unduly yield under an imprinting pressure upon their surfaces, and more particularly to such a printing machine which utilizes rotary carrier and printing elements in operative combination.

A general object of the invention is to provide a particularly effective cooperation between the carrier and printing elements of the machine.

Another object of the invention is to provide an improved and simple hopper means for supplying the articles for imprinting to a plurality of lines of conveyer pockets provided by the carrier.

A further object is to provide an improved means for automatically inking the printing stamps of the rotary printing element.

A more specific object is to provide a branding machine which is particularly adapted for the branding of walnuts and other globate nuts.

An added object is to effect a preferred positioning on the carrier of walnuts, and other globate articles having equatorial ridges, to be branded.

The invention possesses other objects and features of advantage, some of which, with the foregoing, will be set forth or be apparent in the following description of a typical embodiment thereof, and in the accompanying drawings, in which,

Figure 1 is a front elevation of a unitary walnut branding machine embodying the present invention, portions of the structure being broken away.

Figure 2 is a side elevation of the machine.

Figure 3 is an enlarged fragmentary section taken at the broken line 3—3 in Figure 1.

Figure 4 is a fragmentary section at the line 4—4 in Figure 3.

Figure 5 is an enlarged fragmentary section taken in the plane of movement of a printing stamp, and showing the stamp in imprinting relation to a walnut in a carrier pocket.

Figure 6 is a fragmentary plan view of the bottom of the supply hopper.

As is particularly shown, the features of present invention are embodied in the structure of a unitary branding machine of which a suitable frame 11 supports a carrier drum 12, a gravity supply hopper 13, a printing cylinder 14 providing branding stamps 15, stamp inking means including an inking roller 16, means to maintain an ink coating on the inking roller, and power connections for actuating the various moving parts in continuous synchronism. The carrier drum 12 and printing cylinder 14 and inking roller 16 are

respectively mounted on shafts 17 and 18 and 19 which are mutually parallel and are journaled in suitable bearings provided at the opposite sides of the frame.

5 At one frame side, the shafts 17 and 18 respectively mount mutually engaged gears 21 and 22, and these gears are arranged to be driven at an appropriate rotary speed by suitable drive connections from an electric motor 23; in the present instance, said drive connections provide a speed reduction with respect to the motor speed and comprise a pulley 24 on the motor shaft 25, a belt 26 connecting the pulley 24 with a pulley 27 fixed on a counter-shaft 28, and a spur gear 29 fixed on the shaft 28 and meshing with the gear 21.

In the present machine, the carrier drum 12 comprises a cylindric side wall 31 fixed to end discs 32 which receive the shaft 17 axially therethrough and in splined relation thereto for a rotation of the drum with the shaft. The peripheral drum wall 31 is provided with circumferential lines of circular openings 33 which are uniformly spaced in their lines, said openings being

25 somewhat larger than generally globate articles N, which are to be branded by use of the machine. As particularly shown, the articles N comprise walnuts and may hereinafter be so referred to, but no unnecessary limitation thereto of the application of the present novel features is to be

30 thereby implied, as said features may be applicable to the branding of generally globate articles such as other nuts, citrus and other fruits, balls, etc.

35 Outwardly opening cup-like sockets or pockets 34 are provided by cup members 35 mounted at the openings 33, and the cup members are preferably formed of a material which is resiliently yielding and deformable to a slight extent whereby a pocket bottom may more or less conform to the engaged face portion of an article N which is

40 pressed into the pocket by the printing engagement of a branding stamp 15 therewith and so secure the article against rocking during the branding operation. As illustrated, the pocket interiors are spherically curved, and the members 35 are provided with out-turned rim flanges

45 50 which are arranged to seat on the outer face of the peripheral drum wall 31 while the basin portion of a member extends into an opening 33 of the wall. Since the cup members 34 and branding stamps 15 and inking roller faces may be formed of suitable resiliently yielding materials lacking rubber in their compositions, but having the utilized qualities of rubber compositions, any

reference herein to such members as of rubber will be understood to include appropriately functioning rubber substitutes as well as rubber compositions.

Members 37 are provided for securing the rubber cups 35 in the openings 34, each said member having a cylindrically curved cup-engaging inner face provided with an opening for registration with a cup lip opening. The members 37 are under-cut at their said opening to provide a space in which a cup rim flange 36 may be clamped between the member and drum while seated in an opening 33; in the present structure, the members 37 are secured to the drum 12 by means of screws 37' extending therethrough and threadedly engaging the drum side 31. Each member 37 is provided with a transverse extension 38 at a rear portion of its opening; preferably, and as shown, the forward face 39 of the extension is spherically concave as the inner face of the engaged cup 35 to provide a scoop-like extension for the cup. For a reason to be hereinafter brought out, the forward scoop face 39 terminates against the outer rim face of the engaged cup 35 rearwardly of the adjacent cup basin edge to provide a jog or step 40 at the base of said scoop face, this feature being shown in Figure 5.

As illustrated, the printing cylinder 14 is built up of a plurality of pulley-like elements 41 comprising hubs 42, radially ribbed discs 43, and rims 44. The hubs 42 are splined on the shaft 18 and are engaged in end-to-end relation to axially space the rims 44 of the elements as the circumferential lines of sockets provided on the drum 12 are spaced. At approximately spaced points therealong, each rim 44 is provided with radial openings 45 at which the branding stamps 15 are resiliently mounted for solely radial displacement with respect to the carrier drum axis. Each of the present branding stamps 15 is of cylindrical outline having its printing face at one end, and has its base portion fittedly held in a socket 46 comprising an outer part of a member 47, the inner part 48 of said member being of polygonal section and providing a shoulder 49 at its juncture with the part 46.

A cup-like member 51 is fixed against the inner rim face at each rim opening 45 with its recess registering with the said opening and slidably receiving the part 48 through a complementary opening in its bottom to prevent a rotation of the stamp in its mounting. A ring-like member 52 is fixed against the outside of the rim 44 with its bore in alignment with the opening 45, said bore being axially threaded to receive and threadedly mount a tubular member 53 which slidably and complementarily receives the socket part 46 of the member 47 in its bore. At its outer end, the member 53 is provided with an inturned flange 54 for engagement as a stop by the free end of the socket 46, and an helical compression spring 55 disposed about the inner part 48 of the member 47 is constantly operative between the shoulder 49 of the member and the bottom of the member 51 to normally and displaceably engage the outer end of the part 46 with the stop flange 54 which thereby limits the outward extension of each stamp 15 with respect to the printing cylinder in accordance with the adjusted setting of the member 53 in the member 52. As shown, screw bolts 56 are utilized for fixing each member 51 and the ring 52 in position on the rim 44.

It will be understood that articles N in the sockets of the carrier drum 12 and the branding stamps 15 on the printing cylinder 14 would

have the same effective spacing whereby a stamp may printingly engage an article N in an opposed socket when the article is disposed in a common radial line of the drum and cylinder. 5 While the desired relation may be accomplished with drums and cylinders of different effective circumferences, it is preferable that the drum and cylinder have the same effective diameter, as is particularly shown. Correspondingly, the gears 21 and 22 are of like size, with their pitch circumferences lying substantially in the mutually tangent effective cylinders of printing of the carrier drum and printing cylinder; with such an arrangement, the drum and cylinder may not get out of step with each other.

Referring particularly to the showing of Figure 3, it will be noted that each pocket jointly provided by the cup member 35 and the corresponding scoop extension 38 is arranged for movement upwardly through the articles N in the lower portion of the hopper 13 to pick up and gravitally retain a single article N for its movement to the top of the drum 12 for imprinting thereat and its subsequent falling from the socket into a receiving tray or chute 57 at the opposite side of the carrier drum from the pickup point, said pockets first engaging the articles N in the hopper at a point somewhat below the level of the carrier drum axis. The hopper bottom adjacent the zone of action of the pockets is preferably formed to so position the articles N that they may be picked up singly with a minimum displacement of the adjacent articles.

As particularly shown, the sloping hopper bottom 58 is formed with depressed parts 59 providing guideway troughs of generally triangular pyramid form, with their base ends nearest the carrier 12 and in the planes of the circles of the carrier pockets provided on the drum. With this arrangement, articles N in the trough parts 59 are presented against the drum at lower points than elsewhere in the hopper, and the articles so presented may directly enter a pocket coming up from below it and thereafter cooperate with the scoop extension of the pocket to push aside the articles above it as it is moved through the hopper.

The aforesaid pickup action and result may be still further aided by providing the illustrated stepped structure for the diverging sides of the trough 59, this stepping of the hopper bottom portion being preferably such that the leading article in the trough is in front of the riser 60 of the step and generally supports the immediately following articles upon it whereby the effective pressure and resistance of the later articles is primarily downward rather than toward the drum 12. With this arrangement, the danger of crushing the articles in the hopper and a filled pocket is materially minimized while the leading articles in the troughs 59 are successively disposed for their picking up by a scoop and the associated cup directly in the planes of movement of the pockets provided by them.

It will now be noted that when a pocket of the carrier drum is opposite the supply hopper 13 and the carrier drum is being rotated, the frictional engagement of the peripheral drum face and the scoops and the pocketed articles with the free articles in the hopper tends to rotate the pocketed and free articles in a direction opposite that of the drum; this action reduces the effective resistance of the free articles to the rotation of the drum, while preventing a destructive mutual impact or packing thereof.

In the case of more or less globate articles having a radial projection or a stem, the described frictionally induced rotation of each pocketed article is more or less stopped when the projection thereof strikes the socket step 40 forwardly of the scoop bottom; in this manner, the projection may be disposed away from the zone of action of the stamp 15 which is to print on the article when the latter has been moved upwardly to the printing point. This positioning action of the step 40 is particularly valuable with respect to walnuts or other articles having equatorial ridges *n*, it being noted that the described frictional engagement of a pocketed walnut with free walnuts in the hopper will almost invariably dispose the ridge *n* of the walnut flat against the pocket step 40 and so provide for a branding of the pocketed nuts at corresponding convex surface portions lacking the ridge *n*.

In the present machine, ink is supplied to the inking roller 16 from a pick-up roller 61, which comprises a longitudinal side of an ink trough or reservoir 62, by means of a transfer roller 63 which is arranged for alternate engagement with the roller 61 and a roller 64. The roller 64 constantly bears against a roller 65 which in turn constantly bears against the inking roller 16, the rollers 64 and 65 and 16 being engaged along axial lines of their faces with adjustable degrees of pressure in a train which is designed to provide an even coating of ink upon the roller 16. As the printing cylinder 14 revolves, it is arranged to successively present the faces of the branding stamps 15 against the roller 16 for receiving a printing charge of ink therefrom.

Preferably, and as shown, the train of rollers 64 and 65 and 16 is positively driven, with the latter roller having substantially the same peripheral speed as the printing cylinder whereby a constant and uniform supply of ink for the stamps is assured. In the present instance, the driving of the rollers 64 and 65 and 16 is effected by driving the roller 65 from a shaft 66 mounted on the frame 11 generally below the trough 61. As shown, the shaft 66 mounts a gear 67 near one end thereof and operative through idler gears 68 and 69 to actuate a gear 71 mounted at an end of the shaft carrying the roller 65. The appropriate driving of the inking roller 16 is effected by means of a belt 72 connecting pulleys 73 and 74 respectively mounted on extending ends of the shaft 17 of the carrier drum and the shaft 66.

It will now be noted that, for best branding results, the articles N to be printed on must be of substantially the same size; in the case of nuts and other natural or artificial articles which may vary in size, those placed in the hopper would be of a graded size range whereby the branding stamps 15 may be set for use with the average-sized articles of the lot. In setting up the present machine for branding articles N of a given average size, some of the articles are run through the machine and the positioning of the individual branding stamps 15 adjusted radially by adjusting the sleeve nuts 53 until all the stamps on the printing cylinder have their printing faces disposed in a common cylinder of revolution except while they are engaging an article being printed, the radius of said cylinder of revolution being such as to provide a printing pressure of the stamps on the engaged articles which will so press the engaged articles into the yielding cup bottoms as to secure them against rotation or shifting during the branding thereof. In

connection with this seating of a walnut in a cup 35 during its branding, it is to be noted that as a pocketed walnut is raised beyond the walnuts in the hopper, it rocks or rolls in the cup 35 until its flange *n* is no longer opposite the pocket step 40 when the seating and printing pressure is applied; in this manner, the desirable fitted pressing of the positioned walnut into the yielding material of the cup is permitted.

10 When the stamps have been appropriately set in the cylinder, their pressure engagement with the inking roller 16 for their inking may need adjustment; in the present instance, the shaft 19 of the inking roller 16 is carried on and between 15 support forks 75 which are horizontally and independently adjustable on the machine frame 11 to provide any adjustment needed. Following any positioning adjustment of the inking roller, the pressure engagements of the roller 64 with the roller 16 and of the roller 64 with the roller 65 may be adjusted as needed.

The shaft 66 also mounts a pair of generally elliptical plate cams 76 and 77, said cams being respectively utilized for effecting the translation movements of the transfer roller 63 and the periodic rotation of the pick-up roller 61. A rock-shaft 78 is journaled in and between the frame sides below the trough 62 and opposite the roller 65, and mounts arms 79 rotatably carrying the roller 63 between them for swinging between positions of tangential engagement with the rollers 61 and 64. A resiliently flexible arm 81 depends from the rock-shaft 78 into the zone of action of the cam 76, the relation being such 35 that the rotary action of the cam will alternately engage the transfer roller 63 with the rollers 61 and 64; the arm 81 is preferably arranged for its constant engagement against the peripheral working edge of the cam under the influence of 40 a spring 82 which constantly urges an appropriate turning of the rock-shaft. In this manner, a constant rotation of the shaft 66 is arranged to periodically effect a transfer of ink from the roller 61 to the roller 64.

45 The cam 77 is peripherally engaged by the free end portion of an arm 83 which is pivoted on the shaft 84 of the pick-up roller 61 beyond one end of the ink trough 62, and a spring 85 is constantly operative between the arm 83 and an anchorage 50 on the machine frame for constantly engaging the arm 83 with the peripheral edge of the cam 77. The rocking of the arm 83 between limiting positions determined by the eccentricity of the cam is arranged to effect a rotary displacement 55 of the roller 61 during each cycle of operations of the cam through the action of a pawl 86 mounted on the arm 83 and operative against the teeth of a ratchet gear 87 fixed on the shaft 84.

60 As particularly shown, the arm 83 is formed to provide for the pivotal mounting of the pawl 86 thereon for swinging about an axis above and generally parallel to the axis of the roller 61, and the pawl 86 is arranged to so operate against 65 the ratchet gear 87 that the portion of the roller periphery which acts as the front reservoir wall is moved downwardly each time the roller is rotatively shifted through the movements of the arm 83; in the present instance, the pawl 86 is of the hook or drag type, is arranged to gravitally bear against the toothed periphery of the ratchet gear 87, and has its working point operatively engageable between adjacent teeth of the gear 85 only when moving upwardly. With the present 70 arrangement, the pawl 86 is operative to effect

a rotary shift of the roller 61 while the arm 83 is moving toward the shaft 66.

In the present structure, the cams 76 and 77 are similarly disposed with respect to the shaft 66 which carries them. The resulting operation of the arms 81 and 83 which engage the cams at opposite sides of the shaft 66 is such that the roller 61 is rotated while the roller 63 is being laterally translated toward and engages the roller 61, the roller 63 being free for rotation with whichever of the rollers 61 or 64 it is engaging at any particular time.

It will now be noted that the bottom of the cavity of the ink trough 62 is defined by a transversely and resiliently flexible plate 88 fixedly secured at its rear portion and sloping downwardly from its rear edge to dispose its front edge 89 adjacent and along the peripheral face of the pick-up roller 61, said plate being sealedly engaged between trough ends 90. Since the thickness of the layer of ink which is carried from the trough bottom on the roller face as the roller is rotated is determined by the proximity of the front edge of the plate 88 to the roller, means are provided for adjusting the disposal of the forward plate edge with respect to the roller for controlling the quantity of ink available for removal by the transfer roller 63.

As particularly shown, the under face of the forward portion of the plate 88 is engaged by the points of screws 91 which are operative to flex the plate 88 upwardly against its resilient resistance to bending for providing an adjusted scraper action at the roller, it being noted that the path of adjustment of the plate edge 89 intersects the cylinder of the rollers; in this manner, an adjustment of the thickness of the film of ink carried downwardly and forwardly by the roller 61 for removal by the transfer roller 63 may be effected. The screws 91 are shown as threadedly mounted in a plate member 92 underlying the scraper plate 88 and having an upwardly offset rear portion providing the support for the rear portion of the scraper plate.

From the foregoing description taken in connection with the accompanying drawings, the advantages of the construction and operation of the present branding machine will be readily understood by those skilled in the art to which this invention appertains. While I have described the features and principles of operations of a structure which I now consider to comprise a preferred embodiment of my invention, I desire to have it understood that the showing is primarily illustrative, and that such changes may be made, when desired, as fall within the scope of the following claims.

I claim:

1. In a machine for entraining and conveying globate articles having equatorial ridges, a hopper for containing a heaped supply of the articles and having a fixed and inclined bottom, a cylindrical carrier drum having its cylindrical face defining the hopper end at its lower bottom edge and arranged for its rotation about a horizontal axis to move the hopper-defining portion of its cylindrical face upwardly, said drum being provided with a spherically concave article-receiving socket for movement opposite the hopper and having a radial extension at the following side of the socket having its forward face spherically concave as the socket face in rearwardly stepped relation thereto, said extension being arranged to engage beneath a bottom article of the heap in the hopper to move the article upwardly through

the overlying articles of the heap in frictional engagement therewith and for its subsequent disposal by gravity in the associated socket, and means adjacent the hopper bottom operative to direct a bottom article into the path of movement of the extension.

2. A structure in accordance with claim 1 having the socket provided with a facing of resiliently yielding material terminating at the cylindrical face of the drum.

3. In a conveyer for entraining and similarly positioning thereon similar globate articles having equatorial ridges, a hopper for containing a heaped supply of the articles, a carrier provided with an article-receiving spherically concave socket for movement upwardly through and from the heaped supply of articles in the hopper to gravitally receive for rotation therein a single said article in frictional engagement with the overlying articles of the heap, the following portion of the article-engaging socket face being formed to provide a rearwardly extending shoulder for laterally engaging the ridge of the article as a stop to limit the rotation of the article in the moving socket by reason of its frictional engagement with the overlying articles and so retain the mounted article with the plane of its equatorial ridge in predetermined angular relation to the carrier during its subsequent removal from beneath the other articles.

4. In a conveyer for entraining and similarly positioning thereon similar globate articles having equatorial ridges, a hopper for containing a heaped supply of the articles for the individual removal thereof, a carrier having a generally upright portion thereof arranged for its operative upward movement and provided with a spherically concave and substantially hemispherical article-receiving socket having the plane of its mouth generally parallel to its line of movement and having a lateral extension at the following side of the socket having its forward face spherically concave as the socket face in rearwardly stepped relation thereto to provide a shoulder between said socket and extension face, said socket extension being arranged to engage beneath a bottom article of the heap in the hopper to move the article upwardly through the overlying articles of the heap in frictional engagement therewith while a substantial portion of the engaged article extends into the socket space, whereby the equatorial ridge of the article may be brought to laterally bear and be held flat against said shoulder during and by reason of the movement of the article through the heap of articles in the hopper, and means adjacent the hopper bottom operative to direct a bottom article into the path of movement of the extension.

5. In a machine for entraining and conveying globate articles having equatorial ridges, a hopper for containing a heaped supply of the articles and having an inclined bottom, a carrier defining the hopper end at its lower bottom edge and arranged for its actuation to move its hopper-defining portion upwardly, said carrier being provided with a spherically concave article-receiving socket for movement opposite the hopper and being provided with a fixed extension at its following side and extending transversely from the carrier into the hopper space and having its forward face spherically concave as the socket face in rearwardly stepped relation thereto, said extension being arranged to engage beneath a bottom article of the heap in the hopper to move the article upwardly through the overlying

articles of the heap in frictional engagement therewith, and means operative adjacent the hopper bottom to direct a bottom article into the path of movement of the extension.

6. In a machine for entraining and conveying globate articles having equatorial ridges, a hopper for containing a heaped supply of the articles and having an inclined bottom, and a carrier defining the hopper end at its lower bottom edge and arranged for its actuation to move its hopper-defining portion upwardly, said carrier being provided with a spherically concave article-receiving socket for movement opposite the hopper and being provided with a fixed extension at its following side and extending transversely from the carrier into the hopper space and having its forward face spherically concave as the socket face in rearwardly stepped relation thereto to provide a planar shoulder between said socket and extension faces, said extension being arranged to engage beneath a bottom article of the heap in the hopper to move the article upwardly through the overlying articles of the heap in frictional engagement therewith whereby the equatorial ridge of the article may be brought to laterally bear and be held flat against the said shoulder during and by reason of the movement of the article through the heap in the hopper.

7. In a conveyer for entraining and conveying globate articles having equatorial ridges, a continuous hopper for containing a heaped supply of the articles, a carrier provided with a spherically concave article-receiving socket for its upward movement through the hopper and its more or less horizontal movement beyond the hopper, said socket having a radial extension at the fol-

lowing side of the socket with its forward face spherically concave, as the socket face, in rearwardly stepped relation thereto, said extension being arranged to supportingly engage beneath a bottom article of the heap in the hopper to move the engaged article upwardly through the overlying articles of the heap in frictional engagement therewith while said article extends into the associated socket for its subsequent supported disposal by gravity in the socket as the movement of the socket approaches the horizontal.

8. In a machine for entraining and conveying globate articles having equatorial ridges, a hopper for containing a heaped supply of the articles in random positions and providing an upright discharge opening for the gravity discharge of the articles therethrough, and a carrier having a generally upright portion opposite the discharge opening of the hopper and providing an article-receiving spherically concave socket having the plane of its mouth generally parallel to its line of movement and arranged to receive a single and bottom article from the hopper during its upward movement and to remove the received article through overlying said articles in the hopper, said carrier having a lateral extension at the following side of the socket and adjacent the socket and having its forward face spherically concave, as the socket face, in rearwardly stepped relation thereto to provide between the socket face and the forward extension face a shoulder in the plane of the socket mouth and having a width no less than the height of the mounted article.

JARL PEARSON.
